UNITED STATES PATENT OFFICE

157,364

LIQUOR MEASURING GLASS

Robert H. Freshley, South Bend, Ind.

Application April 15, 1947, Serial No. 138,417

Term of patent 3½ years

(Cl. D36—8)

To all whom it may concern:

Be it known that I, Robert H. Freshley, a citizen of the United States, residing at South Bend, in the county of St. Joseph, State of Indiana, have invented a new, original, and ornamental Design for a Liquor Measuring Glass, of which the following is a specification, reference being had to the accompanying drawing, forming part thereof.

Fig. 1 is a perspective view of a liquor measuring glass, showing my new design;

Fig. 2 is a top plan view, and

Fig. 3 is a vertical sectional view thereof taken on line 3—3 of Fig. 2.

I claim:

The ornamental design for a liquor measuring glass, as shown.

ROBERT H. FRESHLEY.
